(57) **CLAIM**

The ornamental design for a front structure of a utility vehicle, as shown and described.

DESCRIPTION

FIG. 1 is a front elevational view of a front structure of a utility vehicle showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front and left side high isometric view thereof;

FIG. 8 is a rear and right side low isometric view thereof;

and,

FIG. 9 is a front and left side high isometric view of the front structure, shown in position of use in the utility vehicle.

The broken line shown in FIG. 9 are for the purpose of illustrating portions of the article and form no part of the claimed design.
